UNITED STATES PATENT OFFICE.

CHARLES C. TOMKINSON, OF PLAINFIELD, NEW JERSEY, ASSIGNOR, BY MESNE ASSIGNMENTS, TO J. EDWARD OGDEN, OF MOUNTAINVILLE, NEW YORK.

EXPANSION SHIELD.

Application filed August 5, 1922. Serial No. 579,566.

This invention relates to improvements in bolt anchors of the character employed for obtaining anchorages in walls of brick, stone or cementitious material not adapted to directly receive a threaded member.

One of the objects of the invention is to provide an expansion shield so constructed and arranged as to possess superior gripping qualities.

10 Another object of the invention is to provide an expansion shield with a separate member adapted to be used in conjunction therewith to provide excess metal, whereby the gripping action of the shield is increased.

15 Another object of the invention is to provide an expansion shield having excess metal on its outer surface for effecting a secure gripping action upon the expansion of the shield.

20 Further objects of the invention will appear from the following description taken in connection with the drawings which form a part of this application and in which

Fig. 1 is a sectional elevation of one form 25 of expansion shield constructed in accordance with the invention.

Fig. 2 is a transverse sectional elevation taken substantially on line 2—2 of Fig. 1.

Fig. 3 is a sectional elevation taken substantially on line 3—3 of Fig. 1.

Fig. 4 is a sectional elevation similar to Fig. 3 but showing a modified form of construction.

Fig. 5 is an elevational view illustrating 35 another form of tubular member adapted to be superimposed on a shield shown in Fig. 1 and to provide excess metal on the outer surface thereof.

Fig. 6 is a view similar to Fig. 5 but showing another form of tubular member.

Figs. 7 and 8 illustrate still further forms of tubular members for providing excess metal on the outer surface of the shield shown in Fig. 1; and

Fig. 9 is a sectional elevation showing the combination of a spiral wound on the outer surface of a shield such as that shown in Fig. 1 with a tubular member superimposed on the spiral.

50 The invention may be briefly described as

comprising an expansion shield preferably formed of sheet metal and having superimposed on its outer surface or positioned therewithin a separate member or separate member for providing excess metal on the 55 surface of the shield. The invention is not limited to any particular type of shield nor is it limited to any particular form of member for providing excess metal and in the drawings various types of shields are shown 60 and various forms of members for providing excess metal are illustrated in connection with the different types of shields.

The shield shown in Fig. 1 comprises two sections 30 and 31 one of the sections having tabs 32 overlapping the other section for securing the two sections together. The sections 31 and 32 are tapered longitudinally to form a constricted bore and the sections are also corrugated to form screw threads 70 for receiving the bolt to be anchored by the shield.

For the purpose of providing excess metal a tubular member 33 consisting of a single piece of bent material is superimposed on 75 and overlaps the outer surface of the inner or more constricted portion of the shield as shown in Fig. 1. When the shield is expanded by the bolt the tubular member 33 will also be expanded and will be pressed into engagement with the bore of the opening in which the shield is inserted thereby effecting a firm and secure gripping engagement with the wall of the opening.

In Fig. 4 the shield 34 is illustrated as 85 consisting of a single piece of bent or rolled material instead of comprising two sections as in the form shown in Figs. 1-3.

Figs. 5 and 6 illustrate still other forms of tubular members which may be used in 90 conjunction with the shield shown in Fig. 1.

Fig. 5 shows a tubular member 35 having slits 36 extending from one end longitudinally thereof to a point adjacent the opposite end. When the member 35 is expanded 95 the slits will permit the spreading of the portions adjacent thereto. The form shown in Fig. 6 is similar to that shown in Fig. 5 but differs therefrom in that the tubular member is corrugated as shown at 37, the 100

corrugations forming screw threads by means of which the member may be screwed onto the inner end of the shield.

In Fig. 7 still another form of tubular member for providing excess metal is illustrated and in this form one end 38 is folded back upon itself, the folded portion extending on the inside of the member and providing a double thickness of excess metal. This member may also be used with the shield of Fig. 1.

In Fig. 8 the tubular member comprises a plurality of sections 39, 40 and 41 superimposed on each other and also forming a plurality of thicknesses of excess metal at the inner end of the shield where the bore is most constricted.

The member shown in Figs. 7 and 8 may be longitudinally slit as shown in Fig. 5 or 20 may be formed from a single piece of material which is bent transversely or rolled into a tube and may expand in the same manner as that shown in Fig. 3.

Fig. 9 shows an expansion shield similar 25 to that shown in Fig. 1 having an elongated spiral 57 threaded thereon and a tubular member 58 superimposed on the shield and spiral, overlaps them adjacent the inner or more constricted portion of the shield.

30 From the foregoing specification it will be seen that an expansion shield has been provided having its parts so constructed and arranged as to effect a secure gripping action.

35 Although several different types of shields have been disclosed and although various methods for providing excess metal have been shown, it will be understood by those skilled in the art that the invention is not 40 limited to the particular embodiments illustrated and described but that further changes in the construction and arrangement of the various cooperating parts may be made without departing from the spirit or 45 scope of the invention as expressed in the following claims.

What I claim is:—

1. A tapered tubular sheet metal expansion shield comprising a tapered tubular 50 threaded member and a different tubular piece of smooth surfaced metal superimposed thereon and forming a separate thickness of metal on its outer surface engaging the peaks of the thread.

55 2. A tapered tubular sheet metal expansion shield comprising an expansible tapered tubular threaded member and a different tubular piece of smooth surfaced metal superimposed thereon and forming a separate thickness of metal on its outer surface 60 engaging the peaks of the thread.

3. An expansion shield comprising a sheet metal longitudinally tapered sectional tubular member having its bore threaded and a 65 separate expansible tubular member mount-

ed thereon at the constricted portion, said member having a smooth surface and engaging the peaks of the thread.

4. An expansion shield comprising a plurality of sections forming a tubular member 70 of uniform thickness, said member being tapered longitudinally to form a constricted bore and having a threaded cross section, and an expansible tubular member consisting of a different piece of smooth surfaced 75 metal encircling the more constricted portion of said first tubular member, and engaging the peaks of the thread to form an additional thickness of metal.

5. A sheet metal expansion shield comprising a plurality of sections tapered longitudinally to form a constricted bore and corrugated to form screw threads therein, and a smooth surfaced member superimposed on and engaging the peaks of the 85 thread on the more constricted portion of the shield to form an excess of metal.

6. An expansion shield comprising a longitudinally tapered sectional expansible tubular member, having its bore threaded and 90 an independent expansible sleeve surrounding the sections and having a plurality of expansible portions engaging said thread.

7. An expansion shield comprising a tubular member uniform in thickness and having a constricted portion adapted for expansion upon insertion of an expanding element therein, and an independent piece of metal superimposed on the outer surface of the constricted portion of the shield, and encircling the shield at the constricted portion thereof and extending longitudinally of the shield, said superimposed metal being expansible with the shield.

8. An expansion shield comprising a tubular member having a constricted portion adapted for expansion upon insertion of an expanding element therein, and an independent tube of sheet metal superimposed on the outer surface of the shield and encircling the shield at the constricted portion thereof and extending longitudinally thereof, said superimposed metal being expansible with the shield.

9. An expansion shield comprising a tubular member uniform in thickness having a larger bore at one end than at the other adapted for expansion upon the insertion of an expanding element therein, and an independent piece of metal superimposed on the outer surface of the smaller part of the shield encircling the shield and extending longitudinally of the shield, said superimposed metal being expansible with the shield.

10. An expansion shield comprising a plurality of sections, one of said sections having means for securing said section to the other section, and means providing excess metal on the outer surface of the shield.

11. An expansion shield comprising a plurality of sections, one of said sections having means for securing said section to the other section, and means including an annular band providing excess metal on the outer surface of the shield.
12. An expansion shield comprising a plurality of sections, one of said sections having means for securing said section to the other section, and means including an annular ¹⁰ split band encircling the shield sections for providing excess metal on the outer surface of the shield.

In witness whereof, I have hereunto set my hand this 2nd day of August, 1922.

CHARLES C. TOMKINSON
